UNITED STATES PATENT OFFICE.

CHARLES W. DWELLE, OF DENVER, COLORADO, ASSIGNOR OF ONE-HALF TO
ROBERT E. WATSON AND ROBERT B. STAPP, BOTH OF SAME PLACE.

THREE-WAY VALVE.

SPECIFICATION forming part of Letters Patent No. 373,819, dated November 29, 1887.

Application filed December 21, 1885. Serial No. 186,361. (No model.)

To all whom it may concern:

Be it known that I, CHARLES W. DWELLE, a citizen of the United States, residing at Denver, in the county of Arapahoe and State 5 of Colorado, have invented certain new and useful Improvements in Three-Way Valves, of which the following is a specification.

The first part of my improvement relates to the construction of the valve proper, which is in form a circular disk containing on its face both a receiving and exhaust port of such form that when the valve is rotated about its stem, which is located at the center of the disk, the receiving-port will correspond with 15 either of the two ports in a corresponding valve-seat to allow of the introduction of steam or other fluid into and through the same, and when again rotated a sufficient distance in the opposite direction will first cover entirely the 20 port in question in the valve-seat by removing the conjunction of the receiving-port of the valve with the corresponding port in the seat, thereby stopping the flow of the fluid through the same, and, next, by being further rotated in same direction will bring the 25 exhaust - port of the valve in conjunction with both the receiving and exhaust ports in the seat, the exhaust-port of the valve, being made of sufficient dimensions and proper 30 form to fully cover the said ports in the seat. Preferably, to the more readily accomplish a perfect correspondence of the ports of the valve and those of the seat the receiving-port of the valve is made of the same dimensions as the ports in the seat, while the 35 exhaust-port is of the size before mentioned to allow of the fluid returning from and through the receiving-port of the seat by which it entered, back by way of the exhaust-port of the 40 valve through the exhaust-port of the seat to the open air or other destination, and in form the ports are four-sided in the shape of segments of a zone, the outer and opposite inner sides of the same being segments of circles de- 45 scribed with the center of the disk or valve-seat as a common center, and the remaining two sides being lines radiating from the same center at angles to each other in the case of the receiving-port of the valve, and both of 50 the ports in the seat of sixty degrees, and in

the case of the exhaust-port in the valve of about one hundred and fifty degrees.

The valve is provided with a socket at its center for the reception of the valve-stem, which fits closely in said socket with but little 55 lost motion, and having a collar which prevents the valve from dropping away from its seat when the pressure is off, should it be necessary or convenient to use the valve in such position as would tend to cause it so to do, 60 the said collar also, by having a bearing against the cap of the valve-chamber, holding the stem in position against being forced out through the stuffing-box by the pressure within, as well as serving to hold the valve in place. 65

The second part of my improvement relates to the construction of the valve chamber, which is preferably cylindrical in form, divided into two parts or chambers by means of a diaphragm across its axis, which diaphragm 70 constitutes the chamber next to the cap or cover, the valve-chamber proper, using the diaphragm as the valve-seat, and having the inlet-opening leading into said chamber, so that the pressure of steam or fluid in the chamber may hold the valve to its place in any position it may be, even with a considerable force tending to rotate it, while the other chamber made by the diaphragm is again divided 75 by another diaphragm in line with the axis of the chamber and at right angles to the first. Leading to each chamber formed by the first with this diaphragm, and on either side of the same, through the first diaphragm or valve-seat, is a port or opening, heretofore spoken of 80 as corresponding to the receiving-port of the valve, while an outlet or pipe-connection is also arranged with each chamber, so that when the valve is turned or rotated into proper position the steam or fluid may pass through the 85 inlet-port of the valve and through either port in the valve-seat into the corresponding chamber, and through its outlet to a reservoir or cylinder in connection with which the valve is used, and upon the valve being rotated in the opposite direction a proper distance the port in question in the valve-seat 90 will be closed by the valve, stopping the said flow to the reservoir, and upon being again rotated in the last-named direction a farther 95 100

proper distance the two ports through the valve-seat into the chambers named will be brought in conjunction with the exhaust-port of the valve, allowing the steam or fluid to return from the reservoir through the port by which it entered, and thence by way of the exhaust-port in valve through the other port in valve-seat and its corresponding chamber and outlet to the open air or other destination.

Referring to the drawings, Figure 1 is an axial half-section of valve-chamber and valve with the valve in position on its seat, O being the chamber, M the first diaphragm or valve-seat, K K' the second diaphragm. (Showu 15 also by dotted lines across the face of the valve-seat in Fig. 4.) N is the valve. L is the valve-stem; Y, the collar on valve-stem. R is the cover of valve-chamber in contact with collar Y, and serving thereby to hold the valve N to 20 the seat M when the pressure is off and when the valve is in such position as to make it desirable. D is the inlet for live steam or other fluid in such position with reference to the valve N that the pressure of the fluid will be on the upper side of the valve and will hold 25 the valve to its seat; and H and E are openings on each side, respectively, of the diaphragm K K', one of which can be used to admit the steam or fluid, when valve is in right 30 position, to the reservoir or other receptacle, while at the same time by proper rotation of the valve the steam or fluid can be shut off from reservoir altogether or allowed to return through this opening by which it entered by 35 way of the exhaust-port in the valve to the other side of the diaphragm K K' and be discharged through the other opening below the valve-seat M into the open air or elsewhere, as may be desired.

Fig. 2 is a top view of the valve proper, showing the inlet or receiving port A, the socket X, for reception of the valve-stem, which may be made circular, instead of rectangular, in form, with a proper feather and feather-way 45 in stem, if preferred, C and C' being the laps of the valve, while B shows the location and form by dotted lines of the exhaust-port S on the under side of the valve.

Fig. 3 shows more clearly the location and 50 shape of the ports by a view of the under side of the valve N, A being the inlet or receiving port, S the exhaust-port, and C and C' the laps of the valve, while the dotted lines surrounding X show the outlines of the socket for the reception of the valve-stem.

Fig. 4 is a top view of valve-chamber with cover or cap removed, showing plan of diaphragm or valve-seat M, with location and shape of the ports A' and B', one on each side 55 of the second diaphragm K K', (shown in dotted lines.) D is the inlet-opening over valve-seat M, and E and H are outlets on either side of diaphragm K K', beneath the first diaphragm or valve-seat M, and communicating, respectively, with the ports A' and B'.

If, now, the valve N be placed upon the seat M in Fig. 1 so that port A, Fig. 2, corre-

sponds exactly with A', Fig. 4, it will be seen that a fluid entering the chamber through inlet D will pass through the port A of valve N, 70 Fig. 2, and the port A' of valve-seat M, Fig. 4, by means of outlet E, beneath valve-seat M, Fig. 4, to a reservoir in connection with the said outlet E. Should the valve then be rotated by means of its stem, so that the lap C, 75 Fig. 2, covers port A', Fig. 4, the flow of the fluid through said port would be stopped, while, if the valve be rotated still farther in the same direction, so that the exhaust-port S, Fig. 2, shall correspond with and cover both 80 the ports A' B' in valve-seat M, Fig. 4, the flow of fluid through E will be at liberty to return through A', Fig. 4, by means of the exhaust-port S, Fig. 2, through port B', by way of the outlet H, Fig. 4, to the open air or other destination. 85

It will be observed that the outlet H, Fig. 4, can be put in communication with reservoir, if needed, instead of outlet E, and the operation repeated in the opposite direction by first 90 making the port A, Fig. 2, correspond to port B', Fig. 4, and by rotating the valve in the opposite way to its first rotation the supply through B' will be first cut off, and then rotating the valve still farther in the same direction its exhaust-port will again be brought over the ports A' B', Fig. 4, this time allowing the fluid to return from H, Fig. 4, by way of said exhaust-port and the ports B' A' in valve 95 to the outlet E, in this case the discharge opening to the air through E instead of H, as before. It will also be observed that owing to the fact that the area of the valve-seat M, Fig. 4, is less by the area of one of its ports than the area of the valve N, Figs. 2 and 3, the pre- 100 ponderance of pressure on the upper or top side of valve N, owing to the difference of area, will keep said valve tightly to its seat, even should the pressure per square inch of area be somewhat greater through back-pressure 105 on the under or lower side of said valve than on the upper side.

I claim as my invention—

1. The casing divided by a horizontal partition, M, and vertical partition K into a chamber above the partition M and two chambers below, and having an inlet-port communicating with the upper chamber and an exit-port to each lower chamber, and ports in the partition above each lower chamber, in combination with a valve turning on the partition M, and having a port extending through the same, and adapted to coincide with either of the ports in partition M, and a larger port or recess in the lower face adapted to connect the ports of the said partition M, all substantially as described. 115

2. The combination, with the valve casing having a valve-seat in a partition above two chambers and a port communicating with each chamber, and a chamber and inlet-port above the partition, of a valve rotating on said seat, and with a port adapted to coincide with either of the ports in the partition, and a recess at 120 125 130

the underside larger than the port and adapted to connect the two ports in the partition, substantially as described.

3. The combination of the valve-seat having two ports communicating with different chambers below, a chamber above having an inlet-port, and a disk-valve turning on said seat, and with two ports, one in the face and the other through the valve, the latter of less area than the combined areas of the ports in the seat and adapted to coincide with either, and

the former larger than said combined areas and adapted to connect the same, substantially as described.

In testimony whereof I have signed my name 15 to this specification in the presence of two subscribing witnesses.

CHARLES W. DWELLE.
